ELECTRIC PLUG

Frederick Pfeiffer, Freeport, N. Y.

Application October 30, 1936, Serial No. 108,490

2 Claims. (Cl. 173—343)

The present invention relates to electric plugs of the two-part type and has for its principal object to provide means for securing the parts of the plug together against accidental displacement.

A further object is to provide an electric plug of this character of simple and practical construction, which is efficient and reliable in performance, relatively inexpensive to manufacture and otherwise well adapted for the purposes for which the same is intended.

Other objects and advantages desired in the details of construction and operation as more fully and hereinafter described and claimed, reference being had to the accompanying drawings forming part thereof, wherein like numerals refer to like parts throughout and in which:

Figure 1 is a side elevational view of a two-part plug in assembled position with the connecting ring shown in section.

Figure 2 is a top plan view.

Figure 3 is a top plan view of the female or bottom section of the plug having its flange formed with opposed flat surfaces.

Figure 4 is a similar view of a modified form of the female part of the plug.

Figure 5 is a side elevational view of a two-part plug showing a modified form of connector ring in section.

Figure 6 is a bottom plan view of the male or upper section of the plug showing the lugs formed on the lower edge of the connector ring.

Figure 7 is a fragmentary sectional view of the female part of the plug and connector ring.

Figure 8 is a side elevational view of the form of connector ring shown in Fig. 5.

Figure 9 is a side elevational of the connector ring shown in section in Fig. 7.

Referring now to the drawings in detail, wherefore in for the purpose of illustration I have disclosed several preferred embodiments of invention, the numeral 5 designates the female or lower part of a two-part electric plug having its upper surface provided with the usual recesses 6 for receiving the prongs 7 of the upper or male part 8 of the plug.

In the form of invention illustrated in Figure 1 of the drawings the part 5 is formed at its upper edge with an annular flange 9 having a groove 10 formed in the outer surface thereof and provided at diametrically opposed side with flat surfaces 11.

The upper part of the plug 8 is likewise formed with an annular flange 12 at its lower edge, said flange likewise being formed with an annular

groove 13 in its outer surface. The part 8 is provided with a connector ring 14 which includes a skirted portion 15 positioned outwardly of the flanges 9 and 12, the inner surface of said skirted portion being formed with vertically spaced annular ribs 16 and 17 seated respectively in the grooves 13 and 10 of the upper and lower parts of the plug. The upper edge of the ring 15 is formed with an inturned flange 18 which overlies and rests upon the flange 12 of the upper part of 10 the plug 8. The lower rib 17 formed on the skirted portion 15, is interrupted, as shown in Figures 7 and 9 of the drawings to provide a plurality of rib sections 19 at the diametrically opposite sides of the ring whereby it will be apparent that in 15 connecting the parts 8 and 5 of the plug that by aligning the sections 19 of the rib with the flat sides 11 of the part 5 of the plug said rib sections 19 will enter the groove 10 and upon a rotation of the ring 15 will secure the parts of the plug 20 against accidental separation.

The flange 18 at the top of the ring is formed with cut out notches 20 at diametrically opposite sides of the ring to accommodate upstanding lugs 21 formed on the flange 12 of the upper part 8 25 of the plug. The lugs 21 constitute stops engaging with the ends of the cut out portions 20 to limit the rotation of the ring 15 whereby to indicate and secure the ring in its locked position.

In the modified form of the invention illustrated in Figure 4 the lower part 5 of the plug may be formed with curved notches 22 in the flange 9 thereof in lieu of the flat sides 11.

In the modified form of the invention illustrated in Figures 5, 6 and 8 the groove may be omitted from the flange 9 of the lower part 5 of the plug and the ribs 19 omitted from the skirted portion 15 of the ring and in lieu thereof the lower edge of the skirted portion 15 is formed with inturned lugs 23 at diametrically opposite sides 35 of the ring for engaging under the lower edge of the flange 9.

It is believed the details of construction and operation of the device will be readily understood from the foregoing without further detail 40 explanation thereof.

What is claimed is:—

- An electric plug including male and female parts, a connector for said parts comprising a ring member rotatably carried by one part of the 50 plug said part of the plug being provided with a flange having an annular groove in its perimeter, said ring member including a skirted portion, an annular rib on the inner surface of said skirted portion seated in said groove to secure the ring

member against removal from said part of the plug, an interrupted annular flange on the other part of the plug and inter-engaging means between the ring member and a last named flange 5 for rotatably connecting same, said inter-engaging means comprising an annular groove in the perimeter of the last named flange and an interrupted rib on the inner surface of the ring member seated in said last named groove and adapted 10 for releasing this said other part of the plug from the ring member upon a predetermined rotating movement of the ring member.

2. An electric plug including male and female parts, a connector for said parts comprising, a 15 ring member mounted on one part of the plug, said part of the plug having a flange provided with an annular groove in its perimeter, said ring member also having a flange overlying the flange of the plug to rotatably secure the ring member

thereto, said ring member including a skirted portion, an annular rib on the inner surface of said skirted portion seated in said groove, an interrupted annular flange on the other part of the plug, inter-engaging means between the ring member and the last named flange for rotatably connecting the same, said inter-engaging means comprising an annular groove in the perimeter of the last named flange and an interrupted rib 5 on the inner surface of the ring member seated 10 in said last named groove and adapted for releasing said other part of the plug from the ring member upon a predetermined rotating movement of a ring member and cooperating means 15 between the first part of the plug and the flange on the ring member limiting rotation of the ring member.

FREDERICK PFEIFFER.
